UNITED STATES PATENT OFFICE.

FREDERICK WILLIAMS, OF SOMERVILLE, MASSACHUSETTS, ASSIGNOR TO ACME REGISTER COMPANY, OF SOMERVILLE, MASSACHUSETTS, A CORPORATION OF MASSACHUSETTS.

STATION-BOX FOR WATCHMEN AND FIRE-ALARM SIGNALING.

1,119,738.

Specification of Letters Patent.

Patented Dec. 1, 1914.

Application filed October 12, 1911. Serial No. 654,304.

To all whom it may concern:

Be it known that I, FREDERICK WILLIAMS, of Somerville, in the county of Middlesex and State of Massachusetts, a citizen of the 5 United States, have invented a new and useful Improvement in Station-Boxes for Watchmen and Fire-Alarm Signaling, of which the following is a specification.

My invention relates to that class of apparatus in which the recording boxes or stations are located in various parts of a building or other place to be protected, the apparatus in the first station being electrically controlled from the central station 10 and each other station being electrically controlled from the one to be visited just previous to it; for my system contemplates a predetermined tour of duty on the part of the watchman and a verification of his 15 20 25 30 35 40 45 50 55 60 65 70 75 80 85 90 95 100 105 110 115 120 125 130 135 140 145 150 155 160 165 170 175 180 low. B is the battery. C is a clock. From the central station proceed three lines forming part of two circuits, each of which includes the battery B, that is, there is what may be termed the main line D which passes from the circuit breaker d to the battery B and thence as D^1 to the point d^1 where it divides, the portion E going to the last station 43, and the portion F forming part of the fire alarm circuit. E^1 is the connection between the first recording station and the clock mechanism, and F^1 the return of the fire circuit.

I will first describe one of the station boxes 23, 33, and 43. All these station boxes are alike except that as each one is expected to give its individual fire alarm signal each is provided with an individual circuit breaker wheel f having a series of teeth f^1 arranged in some predetermined way to ring a signal at the central station. The box shown in Fig. 3, for example, has teeth arranged in two groups of three each so that as the wheel f rotates two separate sets of three strokes each, making the number 33, will be rung at the central station. The ringing is caused by the breaking of a circuit passing through the alarm bell F^2 and including at each station a circuit breaker f^2 forming a contact with the arm f^3 . These parts are normally in contact, but the contact is broken by the engagement with it of one of the teeth f^1 on the moving wheel f in a way well known. The circuit as laid out from the battery B consists in the wire D^1 , the wire F to the arm f^3 in box 43, thence through the circuit breaker f^2 , and wire F^1 to the arm f^3 in the next box, and so on to the alarm bell F^2 at the central station. This bell is of ordinary construction adapted to strike one blow for each time the circuit is broken.

A description of the mechanism for operating the circuit breaker wheel f need not be given as it comprises merely an ordinary train of gears f^4 operated by a spring f^5 wound by the arbor f^9 and an escapement, 100 and restrained from movement under ordinary conditions by a pin f^6 which passes through an opening in the escapement wheel f^7 and engages with a portion of the frame f^8 . When removed the spring f^5 operates the train of gears and the wheel f

which causes the breaking of the circuit and the striking of the bell alarm in the usual way.

The mechanism for operating the fire alarm wheel is located upon a base K upon which is also mounted the recording mechanism which will now be described.

Starting with station 23, e is a screw connection for the incoming wire E¹ which is connected with the circuit breaker e¹. This circuit breaker normally lies against the contact point e² which is connected at the point e³ with the outgoing wire E² of the main circuit, these parts e² and e³ being integral with each other. e⁴ is an arm against which the circuit breaker is pushed at the proper time by means of the push rod J to be described below, and when contact is made with the arm e⁴ circuit is closed through the next box in series as will be below described. This arm has a slight yielding movement and carries a finger e⁵ which runs in a slot e⁶ in the frame to serve as a stop, engaging the end of the slot for this purpose. The push rod J is mounted to slide in the frame j carried on the base and the bearing j¹ and is surrounded by a spring j², one end of which engages with a portion of said frame, the other end being engaged by a pin j³ on the push rod so as to maintain the push rod in such a position as to allow the circuit breaker to remain normally closed. The end of the push rod is provided with insulating material and adapted to engage with the circuit breaker e¹ and break the circuit when pushed. The push rod is normally locked to prevent it from being operated and as shown it is released by means of the armature h operated by the electromagnet H. This electromagnet is in a shunt circuit E²³ which is temporarily operated in the manner below described. The armature h is pivoted at h¹ and is slotted as shown at h², a catch h³ passing down through said slot and adapted to engage under the edge of said slot and hold up the armature from contact with the push rod J when the unlocking of the push rod is desired. The catch h³ is held in position to ride under the armature when the armature is in its highest position by means of a spring h⁴. The push rod J is also provided with a collar j⁴ which normally engages the end of the armature h so that when the armature is in its lowest position as indicated in Fig. 3 the push rod cannot be moved. When, however, the armature has been more certainly attracted by the electromagnet H it is caught in this upward position by the catch h³ as described and is there held so that the push rod may be moved to open the circuit breaker (see Fig. 3). This act of moving the push rod forward, however, also releases the catch h³ from its engagement with the armature as a portion of the collar j⁴

strikes the catch so that the armature is in position to fall, again upon the return of the push rod, and relock the push rod. I have indicated the operation of the armature as being controlled by gravity on the one hand and by the magnet on the other, but it is apparent that if the apparatus be laid horizontally the position of the armature may be controlled by a spring instead of gravity. The frame j in which the push rod J is mounted is in fact a portion of the base of the box or station which is curved upward as indicated in Fig. 4 to allow the formation of a recess and give room for the pushing of the push rod. I provide the base K with a cover K¹ having an opening k against and closing which a sheet of mica k¹ is held by an annular clamp k² which can easily be broken to pull the pin f⁶. All these stations are alike so far as the recording mechanism is concerned so that this description will answer for the description of all the boxes.

I will now describe the operation of my system including the above described signal boxes.

Normally the circuit E, E¹, E², etc., is completed through the series of circuit breakers, one at each station, that is, the wire E¹ runs to the circuit breaker e¹ and the circuit is completed through the contact point e² connected normally at the point e³ with the wire E² and the next station, etc. The circuit breaker d of the watchman's clock at the central station A is operated by means of the rotating dial G forming part of the clock, from which dial project arms g, each in turn adapted to engage and lift the circuit breaker d of the central station and cause it to make electrical contact with the arm d³ and throw it into circuit through the shunt wire E²³. This wire E²³ forms what may be termed a local shunt connected with the electro magnet H in station 23, which electromagnet is also connected with the point e³. This closing of the circuit through d, d³ throws into circuit the shunt E²³ and electromagnet H in place of the wire E¹ and circuit breaker e¹. This change of circuit throws the battery of the electromagnet H and energizes the electromagnet H thereby lifting its armature h and unlocking the push rod J at this station. The current passing from the electromagnet H to the point e³ passes thence by the main circuit back to the clock at the central station. The push rod J is then in condition to be operated. The watchman pushes it to the left at the proper time, this action not only causing its engagement with the circuit breaker e¹ but also causing the recording apparatus at the central station to make a puncture in the dial sheet by means of a puncturing apparatus. The movement of the push rod against the circuit breaker e¹

causes it in turn to break its electrical connection with the contact point e^3 and make contact with the arm e^4 which functionally corresponds with the arm d of the clock, throwing into circuit for the instant the local shunt E^{33} of box 33 which is connected with its electromagnet H , thus causing the energizing of the electromagnet H in the box 33, and freeing the push rod therein so that at the proper time the watchman may push the rod and cause the making of a record from box 33, this act also setting box 43 through shunt E^{43} . The record is made from box 33 because in the pushing of the push rod J in that box the circuit at e^3 in that box is broken for the instant and hence the current which had been passing from the battery B through the recording instrument A^1 , circuit breaker d , wire E^1 , circuit breaker e^1 of box 23, wire E^2 , circuit breaker e^1 of box 33, wire E^2 , circuit breaker e^1 of box 43, and wire E and D^1 being at the moment broken, causes the operation of the recording instrument at A^1 . It will be seen that this operation may be repeated indefinitely according to the number of boxes in the system. Breaking the last circuit at e^3 throws the current temporarily through E . When the watchman has gone his rounds he can do no more until the dial has rotated far enough to bring the next arm g into contact with the circuit breaker d so that the same sequence of operations is gone through again by the watchman. The recording dial G^1 on the clock shows by the punctures in it the times at which the watchman has made his record. This record he can only make by visiting the boxes in a definite order and hence no peculiar record is required for any box.

What I claim as my invention is:

1. In a signal box of the kind described, a push rod, an armature normally engaging and locking said push rod, an electro-magnet located to disengage said armature from said push rod when energized, and a circuit closer normally in engagement with a contact point and located to be disengaged therefrom by the movement of said push rod and to be moved thereby into contact with a second contact point to close a second circuit, in combination with said contact points.

2. In a signal box of the kind described, a push rod, an armature normally engaging and locking said push rod, an electro-magnet located to disengage said armature from said push rod when energized, means adapted to hold said armature in disengaged position and to release said armature upon engagement with said push rod, and a circuit closer normally in engagement with a

contact point and located to be disengaged therefrom by the movement of said push rod and to be moved thereby into contact 65 with a second contact point to close a second circuit, in combination with said contact points.

3. In a signaling system, in combination, a series of signal boxes, a circuit normally 70 closed connecting said signal boxes, each box containing a push rod, an armature engaging and normally locking said push rod, and a shunt circuit containing an electro-magnet adapted when energized to attract 75 said armature to release said push rod, a contact point connected to the electro-magnet circuit in the next succeeding box, a contact point in the main circuit, and a circuit closer normally in contact with said 80 last-named contact point and located to be engaged by said push rod and moved from contact therewith to break the main circuit and into contact with said first-named contact point to close the circuit through the 85 electro-magnet in the next box.

4. In a signal system, in combination, a watchman's clock provided with recording means and having an automatic circuit breaker and means for operating said circuit breaker automatically and periodically, two contacts one normally engaged by said circuit breaker, and the other forming part of a shunt circuit, a series of signal boxes, a main circuit connecting said first-named 95 contact point and said boxes in the series, an electro-magnet in said shunt circuit in the first box and connections between said electro-magnet and said second-named contact point whereby upon the operation of 100 the circuit breaker in said clock the main circuit will be broken and the electro-magnet in said first box will be energized.

5. In a signaling device, a central station comprising a recording mechanism and 105 a circuit breaker, and means for operating said circuit breaker periodically, in combination with a series of signal boxes each containing a circuit breaker, means for locking said signal box circuit breaker in one 110 position, means whereby the operation of a circuit breaker at the central station will unlock the circuit breaker in the first signal box, and means whereby the operation of the circuit breaker in each signal box will cause 115 the operation of said recording mechanism at the central station and the unlocking of the circuit breaker at the next succeeding signal box.
